US0D1072852S

(12) **United States Design Patent** (10) **Patent No.:** **US D1,072,852 S**
(45) **Date of Patent:** **** Apr. 29, 2025**

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventor: **Jennifer Wong**, Breinigsville, PA (US)

(73) Assignee: **Lutron Technology Company LLC**,
Coopersburg, PA (US)

(**) Term: **15 Years**

(21) Appl. No.: **29/920,196**

(22) Filed: **Dec. 8, 2023**

Related U.S. Application Data

(63) Continuation of application No. 29/846,602, filed on Jul. 18, 2022, now Pat. No. Des. 1,013,724, which is a continuation of application No. 29/744,143, filed on Jul. 27, 2020, now Pat. No. Des. 960,897.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of a display screen or portion thereof with graphical user interface showing the claimed design.

The peripheral dashed broken lines illustrate a display screen or portion thereof, and form no part of the claimed design.

1 Claim, 1 Drawing Sheet
(1 of 1 Drawing Sheet(s) Filed in Color)
